MACHINE FOR COVERING KNOCKED DOWN
CARTONS

Samuel Bergstein, Cincinnati, Ohio

Application August 31, 1946, Serial No. 694,192

16 Claims. (Cl. 93—54)

1

My invention has for its main purpose the provision of a machine for applying an exterior, sleeve-like covering to a knocked down carton. By a knocked down carton, I mean a tubular paperboard carton in collapsed form. Such cartons usually comprise a plurality of enclosing body walls in articulation forming the tubular body, there being at the ends of the body walls a series of closure flaps, all as is well understood in the art. Such cartons may take a variety of forms of construction and, of course, may be made in a plurality of sizes and shapes. They do not require special description in this application.

I have found a number of important uses for collapsed or tubular knocked down cartons having the exterior sleeve mentioned above. For example, in my copending application, Serial No. 624,438, filed October 25, 1945, now Patent No. 2,506,057, May 2, 1950, and entitled "Means and Method for Rendering Paperboard Cartons Gas Tight, and Packages So Produced," I have taught the provision of a gas tight package in which the contents may be protected by special atmospheres during shipment and storage. In this package a gas tight sleeve is formed about the enclosing body walls of a carton. When the carton has been filled and closed on both ends, cap like closures of gas tight thermoplastic substance are formed over the ends of the carton in such a way as to join in a gas tight fashion with the end portions of the sleeve. In this way the entire package is made to embody an imperforate gas tight skin or enclosure. The package is then punctured in one or more places and a displacement of the air in the package and the substitution of the desired protective gas are effected whereupon the punctures are resealed.

In the structure of the said copending application, I employ a gas tight sleeve having an independent seam, the sleeve covering at least the body walls of the carton. It is economical to associate the sleeve with the carton as an incident of carton manufacture, and when the carton is in a knocked down or collapsed condition suitable for shipment to the user. One of my objects is the provision of a machine for accompanying this.

Irrespective of considerations of gas proofness, moisture proofness, and the like, the formation of a sleeve surrounding the body walls of a carton has utility in a number of applications. Window cartons may be formed in accordance with my invention by providing one or more openings in the enclosing walls of a paperboard carton and then wrapping the tubular body of the car-

2

ton in a sleeve-like member of transparent or translucent material. This renders unnecessary the use of relatively complicated equipment for spot-locating a sheet of cellophane or the like on a wall of a carton blank, and gluing it in at that position. Moreover, the sleeve formed in accordance with my present invention strengthens the carton and may be employed to impart other desirable characteristics to it, including moisture proofness or the gas tightness which has been mentioned above.

It is an object of my invention to provide a machine which operates to wrap a sleeve about the body walls of a collapsed carton and then adhere it uniformly to those walls throughout their area. Where the sleeve is formed of a transparent material such as the cellulosic or other films of commerce, and where the adhesive employed is transparent and clear in thin layers, any printing or design indicia imposed upon the carton walls is brought out visually by the transparent covering, and the carton is given a glossy and more attractive appearance. This alone will frequently justify the use of the sleeve herein taught.

Yet again it is possible to wrap a knocked down carton in a sleeve of material coated with thermoplastic substance, the sleeve being long enough not only to cover the body walls of the carton, but also to fold over its ends. Such a sleeve may be adhered to the body walls of the carton, but not to the closure flaps thereof. Such a carton may be erected and then closed by merely folding the closure flaps without adhesively securing them. When this is done projecting portions of the liner may then be folded over the ends of the carton; and the carton may be sealed by heat sealing the folded sleeve portions to each other. It is an object of my invention to provide a machine which may be used to form such cartons.

It is further an object of my invention to provide a machine which is simple in construction and low in cost. It is my object to provide a machine which will handle the cartons in collapsed tubular condition as they come from the usual carton folding and gluing machine. It is an object of my invention to provide a machine which will handle the web material for the sleeves in roll or continuous form, which will cut off sheets as desired from the continuous supply, and which will apply these sheets to the blanks automatically, wrapping them tightly about the blanks and adhesively securing them to desired

portions of the blanks, providing also an independent seam in the sleeve so formed.

These and other objects of my invention which will be set forth hereinafter, or will be apparent to one skilled in the art upon reading these specifications, I accomplish by that construction and arrangement of parts and in those structures of which I shall now describe an exemplary embodiment. Reference is made to the accompanying drawings wherein:

Figure 1 is a side elevation of my machine with certain parts cut away.

Figure 2 is an elevational view of the central section of my device taken along the line 2—2 of Figure 1.

Figure 3 is an elevational view of the web feeding and cutting portion of my device taken along the same line in Figure 1, but in the opposite direction.

Figure 4 is a side elevation of my machine from the drive side.

Figure 5 is a partial sectional view on an enlarged scale corresponding to the section line 5—5 of Figure 2.

Figure 6 is a partial sectional view on an enlarged scale showing the first set of wrapping rolls and a guiding and restraining means.

Figure 7 is a partial perspective view of the guide and restraining means.

Figure 8 is a partial sectional view of the machine taken along the line 8—8 in Figure 2.

Figure 9 is a partial elevational view showing a blank feeding means.

Figure 10 is a partial elevational view of a motion transmitting device in connection with the carton feature.

Figures 11, 12 and 13 are partial sectional views showing a web severing device in various positions of operation.

Figure 14 is a perspective view of a carton and sleeve assembly where the sleeve covers and is adhered to the enclosing body walls only of the carton.

Figure 15 is a similar perspective view of a carton and sleeve assembly where the sleeve extends into the region of the closure flaps.

Figure 16 is a partial perspective view of a carton being treated in connection with the first set of wrapping rollers.

Referring first to Figures 1 to 4 inclusive, I provide a machine base having side members 10 and 11 and cross brace members 12. The tops of the side members 10 and 11 form ways upon which certain other elements of my machine may move to provide for adjustment to cartons of different dimensions. Thus, in Figure 1 there is a right end mechanism designated A which is a sheet feeding and severing device. This is mounted for adjusting movement toward and away from a central, stationary mechanism marked B which includes means for feeding tubed cartons, means for handling sheets of web material, and preliminary means for wrapping the sheets about the body walls of the cartons, together with means for delivering the partially wrapped cartons to the next series of machine elements. A mechanism designated as C includes a means for completing the formation and seaming of the sleeve. This mechanism, as a whole, is movable toward and away from the central mechanism B.

Web handling and sheet-forming mechanism

Referring to Figures 1 and 3, the mechanism A comprises a pair of side frames or standards 13 and 14 affixed to a subbase 15, which is slidable along the tops of the side members 10 and 11.

The subbase is provided with racks 16 and 17 meshing with pinions 18 and 19 on a shaft 20 journaled in the base side members 10 and 11 and provided with a hand wheel 21, so that the position of mechanism B may be adjusted along the machine base or bed.

A pair of pinch rolls 22 and 23 are mounted on the side frames in such a fashion that they may withdraw and continuously move a web of sleeve forming material 24 coming to the machine from a roll on an unwinding stand (not shown). The nature of the material is not a limitation on this invention. It will be a flexible sheet stock such as paper, glassine, parchment, laminated foil, or any of the non-fibrous films of commerce. It will preferably have been coated upon one side (which is the upper side in the machine), with a thermoplastic adhesive substance which may be reactivated by heating elements, and which will serve to adhere the flexible sheet material to the carton box. The nature of the thermoplastic adhesive is again no limitation on this invention and may be of any kind suitable to the purposes for which the treated cartons are intended. If the web is not precoated with thermoplastic adhesive, it will be necessary to make provision on my machine for the application of a thermoplastic or other adhesive to the web after or before it has passed through the pinch rolls 22 and 23. This may be done; but an operation with a precoated web is preferred by me.

My invention is not limited to the use of a sheet of sleeve-forming material which is coated all over one of its surfaces with adhesive. For some uses the adhesive may be applied by spotting only, or in selected areas.

The upper pinch roll 22 is journaled in bearings 25 which are slidable on the side frames aforesaid as shown in Figure 1, so that the pinch rolls can separate more or less as required for webs of different thicknesses. The upper pinch roll is driven by a gear or pinion 26 meshing with a gear 27 on the shaft of the lower pinch roll. The shaft of the pinch roll 23 carries a gear 28 which is driven through an intermediate gear 29 on a stub shaft which is adjustable as to position in a slotted ear 30 on the side frame 14. The shaft of the pinch roll 23 is shown as carrying also gears 31 and 32 of different sizes; and the intermediate gear 29 may be selectively brought into mesh with these other rolls for varying the speed of the pinch roll combination. The intermediate gear 29 however, remains in mesh with the axially elongated spur gear 33 on a stub shaft mounted on the side frame 14. The spur gear has a wide enough face to accommodate the intermediate gear 29 in all positions of adjustment; and this gear remains in mesh with the spur gear because the slot 34 in the ear 30 is formed arcuately with its center of curvature at the axis of the spur gear 33. Thus adjustment may be made in a series of steps for the formation of sheets of different longitudinal dimensions.

A bevel gear 35 rotates with the spur gear 33, and motion is transmitted to it by another bevel gear 36 on a vertical shaft 37 journaled in brackets 38 and 39 on the frame of mechanism B and hence movable therewith. A bevel gear 40 on the end of the shaft 37 meshes with a bevel gear 41 splined on the main drive shaft 42 of the machine. This main drive shaft is journaled in brackets 43 and 44 on the side member 11 of the machine bed. An extension 45 of the bracket 39 connects the bevel gears 40 and 41, so that the

latter will move along the shaft 42 as mechanism B is moved along the machine bed.

The pinch rolls 22 and 23 feed the web forwardly; and I provide in connection with mechanism A, a means for severing the web into sheets. This last mentioned means must operate very rapidly so as to make a clean cut across the web 24 without interfering with its progress. It must also be a type of mechanism in which the cutting elements are immediately removed from the path of the web when the cut has been made.

I shall now describe one mechanism suitable for this purpose. The side frames 13 and 14 have upward extensions 13A and 14A, which are connected by a bridge 46. On this bridge I mount an electric solenoid 47, the plunger 48 of which is connected by a link 49 to a crank arm 50 on a shaft 51 journaled in ears on the side frame extensions 13A and 14A. Other crank arms 52 and 53 on the shaft 51 operate a quick cut off mechanism which is detailed in Figs. 11, 12 and 13. Adjacent the pinch rolls 22 and 23 I provide a lower knife mechanism 54 over which the web material 24 passes. This knife is mounted upon a bracket 55 on the standards 13 and 14. The brackets also support means 56 and 57 providing ways for a vertically slideable member 58. This member bears a knife 59 coacting with the knife 54. Spring means 60 and 61 are attached to the vertically slideable member 58 to urge it upwardly; and the other ends of these springs will be connected to some suitable overhead support, which may be the shaft 51. The crank arms 52 and 53 are connected to the vertically slideable member 58 by means of links 62 and 63. These links are provided at their lower ends with angular slots 64 in which pins or a rod 65 attached to the member 58 ride.

When the solenoid 47 is energized to draw the plunger 48 upwardly, it will be evident from Figure 1 that the crank arms 52 and 53 will rotate in a counterclockwise direction, and, through the links 62 and 63, drive the member 58 downwardly, making a cut. It will be seen in Figure 12 that as this motion continues and as the crank arm 52 and link 62 pass dead center, the lower or horizontal portion of the slot 64 will tilt (see Fig. 13), to the extent of causing the rod 65 to slide along the horizontal portion of the slot until it comes beneath the vertical portion. This releases the member 58, and the springs 60 and 61 draw it upwardly instantly. The crank arms and links, upon deenergization of the solenoid, return to the starting position shown in Fig. 11, without again displacing the member 58. Thus the mechanism resets itself in the starting position and is ready for another cycle. Springs 60a on the crank arms and links assist the resetting action.

The mechanism just described is exemplary only of quick cut-off mechanisms which I may employ.

The brackets 55 may as shown, be extended and may be provided with one or more supporting rolls for the severed sheet. Such rolls have been indicated at 71, and gearing for them at 71a. They may be driven by a mechanism hereinafter described.

To energize the solenoid, I provide a switch 72 on the side member 11 of the machine bed. The operating arm 73 of this switch is actuated by a cam 74 on the main shaft 42 of the machine. The switch 72 will be connected to the solenoid and to an appropriate source of power as will be understood by those skilled in the art. To

form sleeves about the bodies of cartons of different sizes will, of course, require sheets of the sleeve forming web material of different lengths. The solenoid 47 will be actuated in a fixed timed relationship to the revolutions of the main shaft of the machine (unless, of course, the cam 74 be changed); but the speed at which the pinch rolls are driven can be varied by causing the intermediate gear 29 to mesh with different ones of the gears 28, 31, and 32 on the shaft of pinch roll 23. In this way the length of the sheets may be varied. The fact that a lapped seam is made in the sleeve enables me to vary the sheet length incrementally.

15 *Carton feeding and initial wrapping mechanism*

Coming now to mechanism B, I have provided standards 75 and 76 on the machine bed. These standards have angular extensions 77 and 78. An arcuate hopper for tubed carton blanks comprises bottom members 79, side members 80, and top members 81. The various members may be adjustably supported at one end by hangers or brackets 82 mounted upon a shaft or rod 83 extending across between the extensions 77 and 78. Adjustability in the hopper is required to accommodate tubular cartons of various sizes, and may be attained by adjusting the members along the brackets, as will be clear from the drawings. The other ends of the hopper members may be supported by hangers or brackets 84 on a shaft 85. The lower hopper members may also be given support from a bar 85a extending across between the table side frames 117 (see Figure 5). The tubed cartons will usually be placed in the hopper by hand.

I provide means for feeding the tubed cartons downwardly one by one. The actual movement of the cartons is accomplished by a vertically reciprocating pair of pusher elements which will be seen at 86 and 87 in Figure 2. The mechanism is detailed in Figures 8, 9 and 10. On the angular side frame extensions 77 and 78, I provide vertical ways 88 and 89. Carriage members indicated at 90 are slideable on these ways, and are connected by a shaft 91, the central portion of which is squared as indicated. Collars 92 are slideable non-rotatively along the shaft 91, and are adjustable by means of set screws 93. The pusher members 86 and 87 are held in holders 94 which are pivoted to the collars 92 as shown in Figure 8. Springs 95 urge those holders against stops 96.

It will be apparent that if the pusher 86 is vertically reciprocated, the end of it, notched as at 97, will engage one of the tubed cartons 98 and carry it downwardly. On the return stroke, the pivoted and spring pressed mounting for the pusher enables it to ride over the next carton, and then spring into position with its notched end engaging the upper edge of the next tubed carton. Reference to Fig. 5 will indicate that the ends of the bottom hopper members 79 serve as abutments to hold the remainder of the tubed cartons in the hopper as the carton 98 is being carried downwardly. Stops 99 on a cross bar 100 between the angular side frame extensions 77 and 78 hold the stack of tubed cartons in the hopper while this feeding action is being accomplished.

The carriages 90 are reciprocated vertically by the mechanism next to be described. Collars 101 (Fig. 10) are rotatively mounted on the rounded ends of the shaft 91; and each such collar has attached to it a headed rod 102, which

passes through a perforation in the end of a lever 103. A spring 104 engaging between the head and the lever permits the rod to move in a controlled fashion with respect to the lever. The lever itself is non-rotatively mounted upon a shaft 105 journaled in the angular frame extensions 77 and 78. A cam follower 106 on a lever 107, which is rotatively mounted on the shaft, is engaged by another lever 103, having a fork with arms lying on both sides of the lever 107. Springs 109 and 110 engage between the arms and the lever 107, giving a resilient construction. A cam 111 for the cam follower is non-rotatively mounted on a shaft 112 journaled in the angular side frame extensions. The shaft is provided with a sprocket 113, and is driven as will hereinafter be set forth.

In my apparatus, it is not necessary to adjust the stroke of the pusher members 86 and 87; but their positions may be adjusted along the shaft 91 by means of the collars 92, for cartons of different dimensions.

Referring now to Fig. 5, it will be seen that as an adjunct to the feeding means just described, I provide a means for urging the stack of tubed cartons forwardly in the hopper. A rod 114 is pivoted as at 115 intermediate its ends to a lever 116 which is fixed on a shaft 119 journaled on table side frames 117 on the angular frame extensions 75 and 76 of apparatus B. A tension spring 118, engaging between the rear end of the rod 114 and the table side frame 117 (or a rod extending between the table side frames) urges the rod counterclockwise on its pivot 115. The front end of the rod bears a frictional means 120, which may be of wood rubber, or other suitable material. A lever 121 fixed to a shaft 122 journaled in the table side frames is so located as to bear against the rod 114. The shafts 119 and 122 are rocked through arcs less than a full circle by mechanisms which will later be described; and the timing is such that while the friction member 120 is moved back and forward in a substantially horizontal direction, it is permitted to contact the lower edges of the stacked tubular cartons on the forward stroke, but is depressed by the end of the lever 121 and held out of contact with them throughout its return stroke.

Immediately below the end of the hopper, electrically heated rolls 123 and 124 are mounted on shafts 125 and 126. The shaft 126 is journaled in the frame members 75 and 76, while the shaft 125 is journaled in blocks 128 slideable in ways in these frame members. Spring means 128 urge these blocks toward the shaft 126 of the other roll, thus providing a resilient pinch roll combination. The ends of the rolls are provided with commutator rings connected with the heating elements inside them; and brushes 129 and 130 are mounted on insulating blocks on the frame member 75 to supply the necessary current. The rolls will be driven as hereinafter described.

The web of material 24 in Figure 5 is moved to the left by the pinch roll combination 22 and 23 and is severed into desired sheets as has already been described. The rolls 11 of apparatus A form the beginning of a table or support which is continued in apparatus B by a stationary member 131 and by guiding and restraining members detailed in Fig. 7, which lie immediately above the pinch of the rolls 123 and 124. It is also continued by such other stationary supporting means as may be required, and by a series of rolls 132 mounted in the table side frames 117.

The guiding and restraining apparatus located

above the pinch of the rolls is shown in Figure 7, as comprising stationary outside means 133 and 134 fastened to end members 135, and a pair of inner members 136 and 137 of more or less elliptical cross section. These are mounted on shafts 138 and 139 which pass through the end members 135 and are provided with levers 140 and 141 and controlling springs 142 and 143. The effect of these springs is to urge the members 136 and 137 to the position shown in solid lines in Figure 7; but, acted upon by a tubed carton coming down from above, they may assume the positions shown in dotted lines in Figure 7 and in solid lines in Figure 6. They act in this position to guide, restrain and straighten out a sheet of the material 24, and smooth it against the sides of the tubed carton 98.

The rolls 11 and 132 in Figure 5 are driven by means hereinafter to be described; and they act to move a severed sheet of the material 24 to the left in that figure. The timing of the various moving elements is such that when the sheet has moved a certain distance to the left, the tubed carton 98 is thrust downwardly against it. This stops the sheet in its path of travel, being enabled to do this because the sheet is merely resting on the driven rolls 11 and 132. The continued downward movement of the tubed carton 98 depresses the members 136 and 137 as shown in Figure 6, so that the sheet begins to wrap about the surface of the tubed carton. The carton and sheet next enter the pinch of rolls 123 and 124. The heat of these rolls softens the thermoplastic coatings on the sheet and causes it to adhere to the body walls of the tubed carton. The timing does not have to be very exact, but is preferably so accomplished that as shown in Figure 5 the sheet 24a is wrapped about the body walls of the carton 98a with an extension 144 occurring on the left hand side of the carton.

As the carton passes out of the pinch of the rolls 123 and 124 it is delivered between pairs of arms 145 and 146 of a spider. The spider is mounted on a shaft 147 journaled in blocks 148 slideable in ways 149 in the frame member 75 and 76. The shaft 147 is turned in a step by step fashion; and the function of the spider is to lower the blank in the direction of the arrow in Figure 5, from the vertical to the horizontal and deliver it to a table 153 which is a part of mechanism C.

The drive for the elements of mechanism B will be best appreciated from Figures 2 and 4. The main drive shaft 42 of the machine carries a bevel gear 151 which meshes with a bevel gear 152 on a vertical shaft 153, having bearings in brackets on the side frame 76.

The block 148 in which one end of the shaft 147 is journaled, and which is slideable on ways in the side frame member 75, is provided with gear teeth 154 along one edge, as can be seen most clearly in Figure 2. This construction is the same at both sides of the machine. Small gears 155 on shafts 156 journaled in the side frames 75 and 76 mesh with these teeth; and the shafts carry sprockets 157 which are connected by chains 159 to sprockets 159 on a shaft 160 journaled on the side frame members. The shaft 160 bears a hand wheel 161 by means of which the blocks 148 may be raised and lowered as will be clear.

On the drive side of the machine the block 148 carries a bracket 162 in which is journaled a bevel gear 163. The gear, being splined to the shaft 153, thus moves up and down with the

block 148, remaining in mesh with the bevel gear 164 of a Geneva movement 165, one part of which is attached to the shaft 147 of the spider. By these means, the spider shaft is driven in a step by step fashion irrespective of its adjusted position.

The shaft 153 also bears a bevel gear 166 which meshes with a bevel gear 167 on the shaft 126 of the heated roll 124. The other heated roll may be undriven; but I prefer to interconnect the shafts 125 and 126 by gears at 168 on the reverse side of the machine. The shaft of the roll 124 on the reverse side of the machine also bears two eccentric cams 169 and 170. The first of these cams has a follower 171 connected by a rod 172 to a lever 173 which is fixed to the shaft 119. This shaft, by a mechanism already described, causes the horizontal back and forth movement of the frictional means 120 beneath the stack of cartons. The other eccentric cam 170 has a follower 174 which is attached to a lever 175 on the shaft 122. The rocking movement of this shaft moves the lever 121 up and down, controlling the contact of the frictional means with the cartons.

A gearing indicated at 176, permitting changes of speeds, may be interposed between the bevel gear 167 and the shaft 126 if desired.

A bevel gear 177 meshes with the gear 176 and is fixed to a vertical shaft 178 journaled in brackets 179 and 180 on the side frame member 76 and the angular extension 78. The shaft bears an upper bevel gear 181 meshing with a bevel gear 182 on a horizontal shaft 183 journaled partly in an extension of the bracket 180 and partly in the member 78. The shaft 183 also carries a sprocket 184 which is connected by a chain 185 to the sprocket 113 on the shaft 112 which drives the pusher mechanism heretofore described.

The various rollers 71 and 132 are preferably, though not necessarily, separately driven. The rollers 132 are connected together by a gearing indicated at 186 in Figure 4, so that all of these rolls turn in the same direction. The rollers 71 are similarly geared together at 71a. In Figure 2, I have shown a small motor 187 mounted on a bracket 188 on the frame member 75. The shaft of this motor bears two sprockets 189 and 190 which are connected respectively by chains 191 and 192 to sprockets on the ends of the shafts of one of the rolls in each of the groups 71 and 132. One of these sprockets is indicated at 193. The other is not shown.

Final wrapping and delivery means

Mechanism C, as will be seen from the various figures, comprises a pair of side frames 194 mounted on a subbase 195 which is slidable on the side members 10 and 11 of the machine bed. The members 195 are provided with gear teeth 196 meshing with pinions 197 mounted on a shaft 198 journaled in the side members 10 and 11, and provided with a hand wheel 199. Thus mechanism C as a whole may be moved toward and away from mechanism B to accommodate different sizes of cartons.

The side frame members 194 of mechanism C have vertical ways 200 in which members 201 are slidable. The table 150, to which reference has already been made, is mounted on a bracket extending between the members 201. A shaft 202 for a lower heated roll 203 is journaled in the members 201. These members also provide ways 204, slidably holding blocks 205 in which the shaft 205 of an upper heated roll 206 is jour-

naled. A spring 207 engages between the block 208 and upper abutment 209 on the member 201, thus providing a resilient pinch for the rolls 203 and 206.

To each of the members 201, I rigidly attach a threaded shaft 210 extending downwardly. A threaded nut 211 bearing a worm wheel 212 engages each of these shafts, and is retained between the arms of a transverse member 213 on the side frame 194 in such fashion that, while it can rotate, it cannot move vertically. A worm 214 on a shaft 215 journaled in the transverse members 213 serves as means for concurrently turning the worms and hence the worm wheels, thus raising and lowering the members 201 whereby to adjust their positions with respect to the position of the spider in mechanism B. The shaft 215 is provided with a hand wheel 216 (Fig. 1).

As indicated above, the spider delivers the partially wrapped carton onto the table 150, whence it will be sent through the pinch of the heated rolls 203 and 206. As the carton comes into position on the table, a guide means 216a adjacent the roll 206 assures the turning of the projecting portion 144 of the wrapper sheet 24a, and its smoothing back over the other edge of the wrapper sheet so as to complete the wrapping and the formation of a seam in the wrapper sheet.

To move the partially wrapped carton from the table 150 into the pinch of the rolls 203 and 206, I provide a pusher lever 217, pivoted as at 208 to the side frame 76 of mechanism B, or to the block 148. The lower end of this lever is connected by a link 219 to a lever 220 on a shaft 221 extending across between the members 201 of mechanism C. The shaft 221 also has a lever 222 with a cam follower. A cam 223 is fixed to the shaft 205 of the heated roll 206. A spring 224 operates to hold the cam follower against the cam; and it will be apparent that as the roll 206 rotates, the carton 98b will be pushed from the table 105 into the pinch of the rolls 203 and 206.

These rolls are electrically heated, being provided with contact rings as before described. Brush supports are shown in Figure 5 at 225 and 226. The wrapping of the carton is completed by these rolls, and the finished article may be delivered to a conveyor 227 or other receiving means forming no limitation on this invention.

The rolls 203 and 206 are geared together by gears 229 and 230 (Figure 4). A bevel gear 230 is fastened to the last mentioned gear, and meshes with a bevel gear 231 on a vertical shaft 232. This shaft is journaled non-slidably in an upper bracket 233 on the vertically slidable member 201, and slidably in a lower bracket 234 on the subbase of mechanism C. A helical gear (not shown) is splined on the shaft 232, and meshes with a helical gear 235 splined on the main drive shaft 42; and the meshing of these gears is maintained in spite of movement of mechanism C by the engagement of helical gear 235 with the bracket 234. In this way the rolls 203 and 206 are driven.

In Figure 14 I have shown a paperboard carton 236 having conventional enclosing body walls and end sealing flaps. A wrapper sheet 237 has, by the use of my machine, been wrapped about the body walls of this carton and seamed at 238. In the light of the discussion in the preamble of this specification, it will be clear that this wrapping may be for the purpose of providing the carton 236 with a gas tight, independently

seamed sleeve, and that the carton may be intended for the production of a gas tight package in which the contents are preserved in a special atmosphere. In addition, or instead of a gas tight feature, the carton may have been wrapped to provide a window package, in which event one or more of the body walls of the carton 236 will have window openings in them which are covered by the transparent wrapping. Again, instead or in addition, a transparent glossy wrapping may have been applied to bring out the printed indicia on the carton walls, and to give an enhanced appearance to the package. It will be noted in Figure 14 that the wrapping or sleeve 237 covers the body walls of the carton and does not extend into the area of the sealing flaps. Such wrapped carton may be made on my machine in various sizes with heated roll combinations of any length beyond the width of the wrapping itself.

In Figure 15 however, I have shown a carton 239 provided with the wrapping 240, seamed as at 241. In this instance the wrapping not only covers the body walls of the carton, but extends into the areas of the closure flaps. In cartons lapped in this fashion, it is generally desired that the wrapping adhere uniformly and smoothly throughout the areas of the body walls but be unadhered to the flaps. This may be accomplished by employing heated rolls such as the rolls 123, 123a, and 124a (corresponding to the rolls 123 and 124 of Fig. 5), but with their faces so limited in longitudinal extent as to contact only the body wall portions of the carton. It will be understood that rolls corresponding to the rolls 203 and 206 of mechanism C will be employed similarly limited in the axial extent of their working faces. Through the use of such rolls, a wrapper, even though it extends into the closure flap area, can be adhered only to the body walls of the carton and will be unadhered to the flaps.

A carton such as is shown in Figure 15 may be erected and closed by simply folding the closure flaps without adhering them, afterward folding the unadhered end portions of the wrapper over the ends of the carton and sealing the parts together. This may be done by means of the thermoplastic adhesive already resident upon the wrapper sheet; and the sealing may be done by members heated sufficiently to reactivate the adhesive. This is an excellent and inexpensive way of providing wrapped cartons for various purposes, particularly where preservation of the moisture content of the packed articles is desired. It will be understood that a wrapped carton may be made in which the sleeve member is merely spotted or attracted at intervals to the body walls of a carton, if desired. Wrapped structures may also be made in which the inner carton is provided with other than the usual seal-end type closure flaps, for example, a tuck-end closure-flap arrangement, or the type of flaps which come into interengagement when folded over and depressed, or with any of the known, self-erecting closures. Also for the formation of certain types of wrapped structures, my machine may be employed to apply a sleeve to a tubular paperboard body devoid of closure flaps.

Adhesive may be applied to the sleeve web either on my machine or in a previous operation, in selected areas only rather than over one entire surface of the web. Thus if a band of adhesive having a width equivalent to the length of the body walls is applied to the web, my machine will

form a sleeve about a tubular carton with the sleeve extending into the flap area, adhered to the body walls, but not adhered to the flaps. In this event the length of the heated rollers does not need to be limited to the length of the body walls. A sheet or web of sleeve forming material may likewise be coated with a band of adhesive of a width equivalent to the length of the body walls plus a transverse band of adhesive extending all along and limited to the projecting portion 144 of the wrapper sheet as it is applied to the carton body in the first wrapping operation. In the second wrapping operation, using heated rollers of a length at least equal to the length of the sleeve, the sleeve will be seamed throughout its length but will remain unadhered to the flaps.

Any of the cartons herein described may be provided with cut-outs in one or more walls, a transparent, external sleeve or wrapping furnish-ing a window.

Modifications may be made in my invention without departing from the spirit of it.

Having thus described my invention in an exemplary embodiment, what I claim as new and desire to secure by Letters Patent is:

1. In a machine of the character described, a pair of rolls juxtaposed and forming a pinch, means to feed a sheet of material to a position in a plane adjacent said rolls and substantially parallel with the plane containing the axes of said rolls, and means for feeding a tubed carton into the pinch of said rolls through the plane occupied by said sheet whereby to carry said sheet through the pinch of said rolls and wrap it about 35 side portions of said tubed carton with one end projecting, means to turn said partially wrapped carton through an arc, means for sweeping back said projecting portion of said sheet as said carton is so moved, and a second pair of pinch rolls through which said carton is next sent to press 40 said projecting portion of said sheet against said carton and lap it over the opposite edge portion of said sheet.

2. The structure claimed in claim 1 including means for heating said rolls whereby a sheet 45 coated with a thermoplastic adhesive may be caused to adhere to said carton with the lapping portions of said sheet adhering to each other.

3. In mechanism of the class described, a pair 50 of horizontally arranged pinch rolls, means above said pinch rolls for supporting a sheet of flexible material, a hopper for tubular cartons above said supporting means and means for feeding said cartons downwardly one by one into the pinch of 55 said rolls whereby a carton so fed is enabled to carry said sheet with it through the pinch of said rolls, a spider located below said rolls to receive said carton and sheet, means for operating the spider to deliver the carton and sheet in a horizontal plane at a lower level and a pair of 60 vertical pinch rolls located at said level to receive said carton and said sheet.

4. In mechanism of the class described, a pair 65 of horizontally arranged pinch rolls, means above said pinch rolls for supporting a sheet of flexible material, a hopper for tubular cartons above said supporting means and means for feeding said cartons downwardly one by one into the pinch of said rolls whereby a carton so fed is enabled to 70 carry said sheet with it through the pinch of said rolls, a spider located below said rolls to receive said carton and sheet, means for operating the spider to deliver the carton and sheet in a horizontal plane at a lower level and a pair of vertical 75 pinch rolls located at said level to receive said

carton and said sheet, and means substantially at the level of said supporting means to withdraw sheet material from a roll and to sever it into said sheets.

5. The structure claimed in claim 4 wherein said mechanism includes a machine base, a first support on said base supporting said first pair of rolls, said hopper and said spider, a second support on said base supporting said second pair of rolls, and a third support on said base supporting said withdrawal and severing means, one at least of said supports being movable on said base for adjustment relative to a second of said supports, and means for moving said movable support.

6. In a machine of the character described, a machine bed, central supports on said bed, a hopper for tubed cartons, a support for sheets of flexible material below said hopper, a pair of horizontal pinch rolls and receiving means for a wrapped carton located on said central supports, additional supports movable on said machine base and supporting a pair of pinch rolls arranged vertically, said last mentioned supports being movably mounted for movement toward and away from the first mentioned supports on the machine bed, and means for moving said movable supports.

7. In a machine of the character described, means for withdrawing coated web material from a roll, quick acting means for severing said web into sheets, a pair of horizontally arranged pinch rolls, means for positioning a sheet above said rolls, means for feeding a tubed carton downwardly into the pinch of said rolls, said carton feeding means and said sheet positioning means acting in timed relation to cause the sheet to be contacted by the carton and carried with it into the pinch of said rolls, the sheet being of a size and positioned so as to be wrapped by the rolls about body wall portions of the carton with an edge projecting beyond the upper end of the carton, means beyond said rolls for folding the projecting edge of the sheet over the upper end of the carton so as to lap the opposite edge of the sheet, and sealing means in the form of a second pair of pinch rolls for sealing together the lapped edges of the sheet, and means for passing the wrapped cartons through said second pair of rolls to complete the wrapping and sealing thereof.

8. The structure claimed in claim 7 including means for heating said pinch rolls so that a sheet of said web material coated with a thermoplastic substance may be cemented to said carton and separately seamed as to its lapping edges.

9. In a machine of the character described, a first mechanism comprising means for withdrawing coated web material from a roll and for severing it into sheets by quick acting means, a second mechanism comprising a support for the severed sheets, a pair of pinch rolls located below said support, means for heating said pinch rolls, a hopper for tubed cartons located thereabove and means for feeding individual tubed cartons so as to carry sheets of said web material into the pinch of said rolls, and a means for receiving the partially wrapped cartons so produced, and transferring them from said second mechanism to a third mechanism and a third mechanism comprising a support for the transferred cartons, means for folding over a projecting end of said sheet and a second pair of pinch rolls to receive the carton and sheet and complete the wrapping and sealing thereof.

10. In a machine of the character described, a first mechanism comprising means for withdrawing coated web material from a roll and for severing it into sheets by quick acting means, a second mechanism comprising a support for the severed sheets, a pair of pinch rolls located below said support, means for heating said pinch rolls, a hopper for tubed cartons located thereabove and means for feeding individual tubed cartons so as to carry sheets of said web material into the pinch of said rolls and wrap said sheets about wall portions of said cartons with a projecting edge, and a means for receiving the partially wrapped cartons so produced, and transferring them to an angularly related plane, and a third mechanism comprising a support for the transferred cartons, means for folding over the projecting edge of said sheet and a second pair of pinch rolls to receive the carton and sheet and complete the wrapping thereof, said several mechanisms being movable toward and away from each other for adjustment for cartons and sheets of varying dimensions, and means for moving the said several mechanisms for relative adjustment.

11. In mechanism of the character described, a support for sheets of web material comprising in part driven rolls upon which a sheet may be supported, and tending to move said sheet, a pair of pinch rolls located below said support and means above said support to feed a tubed carton into the pinch of said rolls through the plane of said support whereby said carton may arrest the movement of a sheet upon said support and carry it into the pinch of said rolls, said carton passing through the pinch of said rolls with said sheet, whereby said sheet becomes at least partially wrapped about body portions of said carton.

12. In mechanism of the character described, a support for sheets of web material comprising in part driven rolls upon which a sheet may be supported, and tending to move said sheet, a pair of pinch rolls located below said support and means above said support to feed a tubed carton in timed relation to the movement of the sheet to engage the sheet and carry it into the pinch of said last mentioned pinch rolls through the plane of said support whereby said carton will arrest the movement of a sheet upon said support, said carton passing through the pinch of said rolls with said sheet, whereby said sheet becomes at least partially wrapped about body portions of said carton, means for heating said rolls, the working faces of said rolls being confined in length to substantially the length of the body walls of said carton whereby sheets coated with a thermoplastic adhesive substance may be wrapped about and caused to adhere to the body wall portions only of said cartons.

13. In a machine of the character described, means for withdrawing a supply of coated web material from a roll, quick acting means for severing said material into sheets, a pair of pinch rolls, a support for said sheets adjacent said pinch rolls, means for positioning a sheet on said support, a hopper for tubed cartons, means for feeding cartons one by one from said hopper through said support into the pinch of said rolls so as to cause a sheet positioned on said support to be carried with the carton into the pinch of the rolls, the sheet being of a size and positioned so as to be wrapped by the rolls about body wall portions of the carton with an edge projecting beyond the upper end of the carton, means beyond said pinch rolls for holding the projecting

edge of the sheet over the upper end of the carton so as to lap the opposite edge of the sheet, and a second pair of pinch rolls for sealing together the lapped edges of the sheet to complete the wrapping and sealing of the carton, and means for driving said withdrawing means, said quick acting means, said first mentioned pinch rolls, and said carton feeding means in timed relationship.

14. The structure claimed in claim 13 including adjustable means for varying the longitudinal dimension of the cut sheets, and adjustable means for varying the space relationship of the said driven elements to accommodate cartons of different sizes.

15. The structure claimed in claim 13 wherein said support comprises movable elements acting to restrain and smooth said sheet against body wall portions of said carton as the carton and sheet enter the pinch of said first mentioned rolls.

16. A process of producing wrapped cartons which comprises providing a tubed carton and a wrapper sheet of a size to enclose the body walls of said carton, positioning said wrapper sheet above a pair of heated pinch rolls, passing said carton downwardly into the pinch of said rolls, said sheet being positioned so as to

5

10

15

be contacted by said carton and carried with it into the pinch of the rolls, the positioning of the sheet being such that it will be wrapped about body wall portions of the carton with an edge projecting beyond an end of the carton, thereafter folding the projecting edge of the sheet over the end of the carton so as to lap the opposite edge of the sheet, and then passing the wrapped carton through heated pinch rolls to secure the lap portions of the sheet to each other.
